UNITED STATES PATENT OFFICE.

LAMBERT SNYDER, OF ROCHELLE PARK, NEW JERSEY, ASSIGNOR TO
THE LAMBERT SNYDER COMPANY, OF NEW YORK, N. Y.

VIBRATILE APPARATUS.

SPECIFICATION forming part of Letters Patent No. 773,234, dated October 25, 1904.

Application filed August 27, 1903. Serial No. 170,908. (No model.)

To all whom it may concern:

Be it known that I, LAMBERT SNYDER, a citizen of the United States, and a resident of Rochelle Park, in the county of Bergen and State of New Jersey, have invented certain new and useful Improvements in Vibratile Apparatus, which improvements are fully set forth in the following specification.

My invention relates to devices for producing vibrations to be applied to the body of a patient undergoing vibratory massage treatment; and its object is to provide a vibration-generator of a simple and inexpensive character which shall be durable, efficient, and easily applied and one which cannot get out of order.

The invention consists in the novel disposition and relative arrangement of the various coöperating parts thereof, whereby the attainment of the foregoing objects is rendered practicable, in certain combinations, and in certain details of construction, all of which will be specifically referred to hereinafter and set forth in the appended claims.

The invention is clearly illustrated in the accompanying drawings, wherein similar reference-numerals denote corresponding parts.

As to said drawings, Figure 1 is an elevation of a vibratile apparatus constructed in accordance with my invention. Fig. 2 is an end view thereof, the stop ordinarily made use of being removed. Fig. 3 is a detail sectional view showing the coöperative relation existing between the main staff and the traveling head made use of, the scale being enlarged.

In a general sense my present invention comprises a main staff and a vibrator-head, the latter mounted for movement longitudinally on the staff in such manner that said movement will give a series of shocks to the staff, which may be communicated to the body of a user.

In carrying out my invention, reference being had to the accompanying drawings, I essentially make use of a main staff 2 and a traveling head 3, the latter being mounted on said staff for movement longitudinally there-

along. The staff 2 may be formed from any suitable material, as metal, and may be of any appropriate cross-sectional contour. The foregoing remarks with reference to the material of the staff 2 also apply to the material of the head 3, save that in this instance the material is non-resilient and the said head 55 may be of any appropriate general contour. The diameter of the opening 4 of the head 3 is somewhat greater than the diameter of the staff 2. Under the foregoing conditions the head 3 may be intermittently moved or 60 caused to undergo a multiplicity of steps in either direction along the staff 2 by properly applying pressure to said head. To insure the most satisfactory vibratory results, such applied pressure should be substantially constant and uniform and should be applied in a direction parallel or approximately parallel with the staff 2 at a point or points somewhat removed radially from said staff. Under the application of pressure to the head 3, as 70 stated, said head is caused to alternately move into and out of a binding or frictional engagement at the opposite terminals of its opening 4 with the staff 2, and when moved into such engagement the resulting impact produces a vibratory action along said staff, and this vibratory action in turn aids in effecting the release of said head from its said engagement with the staff 2.

The foregoing alternate binding and releasing action of the head 3 is maintained under the applied pressure and until said head shall have moved intermittently or step by step from one end to the other of the staff 2, said head accordingly moving a degree or step 85 along said staff during each momentary release of said head from its binding engagement with the staff 2. To facilitate the application of pressure to the head 3, I purpose to conjoin with the latter a radial arm 5, which 90 thus partakes of the vibratory action imparted to the staff 2 in the practical operation of my improved apparatus. The relative proportions of the staff and arm may be varied, as may be found expedient to secure the best re- 95 sults.

In order that the staff 2 may be applied directly to the body of the person using the apparatus, I provide it with a contact member 6 at one end which, as I have shown it, may 5 be formed by bending the staff at right angles to itself and then returning it upon itself, such returned portion being slightly concave to approximate the curves of the human body. Any other form of contact member might be 10 used, however, it being merely essential to provide some means whereby the vibrations generated in the staff may be communicated to the body. In order that the other end of the staff may be held easily, I provide it with a 15 removable stop 7, recessed to receive the end of the staff.

In operation the contact member 6 is held against any desired part of the body and the traveling vibrator-head 3, through the arm 5, 20 is moved at a proper degree of speed back and forth on the staff. This movement by reason of the construction of the head gives a series of sharp shocks or vibrations to the staff which in turn are communicated to the contact member and the body of the patient. Where the patient himself is using the device he grasps the stop 7 in one hand, presses the contact member against his person, and with his other hand moves the arm 5 and head 3 25 back and forth, or the end of the staff may be placed against a support and the head 2 moved back and forth, the contact member being applied to any part of the body needing treatment, and the device used in any manner 30 most convenient. It is not necessary, however, that the vibrations be communicated through the staff itself, as the arm 5 will also 35 transmit vibrations to the body.

For the generation in the staff of vibrations 40 adequate for massage purposes two requisites are essential, first, that the contact blow of the head on the staff should be sharp and decided, and second, that the shock of such blow should be transmitted longitudinally along 45 the staff and not be taken up by any sidewise resiliency in the staff. Resiliency in the staff or head which takes up this impact shock destroys the adequacy of the vibrations for massage treatment, and while I do not wish to be 50 limited by the term "rigid," as used in the claims, to absolute and complete rigidity in either staff or head I disclaim any device of like construction with mine wherein the staff and the head, either or both, are insufficiently 55 rigid to generate and transmit shocks practically strong enough and sharp enough to be used for massage purposes.

Having described my invention, what I claim is—

60 1. A vibratory massage apparatus comprising a rigid staff; a rigid head, said head being arranged to travel, under pressure suitably applied thereto, step by step to and fro along, and hence momentarily engage and release said 65 staff, the engaging effect of said head with said

staff being accordingly non-elastic, and vibrations adequate for massage purposes being accordingly imparted to said staff; means whereby pressure may be applied to said head as stated; and means for transmitting to the body 70 of a patient the vibrations so produced, substantially as described.

2. A vibratory massage apparatus comprising a rigid staff; a rigid head, said head being arranged to travel, under pressure suitably 75 applied thereto, step by step to and fro along, and hence momentarily engage and release said staff, the engaging effect of said head with said staff being accordingly non-elastic, and vibrations adequate for massage purposes being accordingly imparted to said staff; and a body-contact member on said staff for transmitting to the body of a patient the vibrations so produced, substantially as described.

3. A vibratory massage apparatus comprising a rigid staff; a rigid head, said head being arranged to travel, under pressure suitably applied thereto, step by step to and fro along, and hence momentarily engage and release said staff, the engaging effect of said head with said 80 staff being accordingly non-elastic, and vibrations adequate for massage purposes being accordingly imparted to said staff; means whereby pressure may be applied to said head as stated; and a detachable stop on the end of said 85 staff for preventing removal of the head from the staff in the direction of said stop, substantially as described.

4. A vibratory massage apparatus consisting of a rigid staff, a traveling rigid vibrator-head loosely mounted on the staff, the said head having diagonally opposite staff-contact points, an arm extending from said head, whereby when pressure is applied to said arm 100 the head will travel along said staff with a 105 step-by-step movement and impart to the staff vibrations adequate for massage purposes, and means for transmitting vibrations so produced to the body, substantially as herein specified.

5. A vibratory massage apparatus consisting of a rigid main staff, a body-contact member thereon, a rigid vibrator-head mounted on the staff, and having diagonally opposite staff-contact points, said head being extended outwardly at one side of said staff and being then 110 adapted as described to travel along said staff with a step-by-step movement and impart to the staff vibrations adequate for massage purposes, substantially as herein specified.

6. A vibratory massage apparatus consisting of a rigid main staff, a body-contact member thereon, a rigid vibrator-head mounted on the staff, and having diagonally opposite staff-contact points, and being thereby adapted to travel along said staff with a step-by-step 115 movement and impart to the staff vibrations adequate for massage purposes, and an arm extending outwardly from said head, substantially as herein specified.

7. In an apparatus for creating massage vi- 120

brations, the combination with a rigid main staff, a body-contact member thereon, and a detachable stop at one end of the said staff, of a rigid vibrator-head having an opening for 5 the passage of the staff and having diagonally opposite staff-contact points, and an arm projecting outward from one side of said head whereby when pressure is applied to said arm

the head travels along said staff with a step-by-step movement and imparts to the staff vibrations adequate for massage purposes, substantially as herein specified.
